UNITED STATES PATENT OFFICE.

LAWRENCE WALUCH, OF BALTIMORE, MARYLAND.

NECKTIE HOLDER.

1,408,151.

Specification of Letters Patent. Patented Feb. 28, 1922.

Application filed September 6, 1917. Serial No. 189,997.

To all whom it may concern:

Be it known that I, LAWRENCE WALUCH, citizen of Austria, residing at Baltimore, in the county of Baltimore City and State of Maryland, have invented certain new and useful Improvements in Necktie Holders; and I do hereby declare the following to be a full, clear, and exact description of the invention, such as will enable others skilled 10 in the art to which it appertains to make and use the same.

This invention relates to improvements in necktie holders.

The object of this invention is to provide 15 a holder about which a tie is adapted to be formed in the usual four-in-hand knot, and the holder supporting the tie in this position, permitting the same to be readily and quickly attached to the collar button and 20 position the same properly within the collar.

A still further object of this invention is to provide a necktie holder or former adapted 25 to be constructed of a single length of material and in such a manner that a tie may be quickly and easily formed thereon into a four-in-hand knot.

A still further object of this invention is to provide a necktie holder of this character, which will be simple, practical and compara- 30 tively inexpensive in construction and one that can be manufactured and sold at a low cost.

With these and other objects in view, the invention consists in the novel combination 35 and arrangement of parts hereinafter more fully described and set forth in the claims hereto appended.

In the drawing:

Figure 1 is a front elevation illustrating 40 a necktie secured to my improved holder.

Figure 2 is a rear elevation of the same,

Figure 3 is a transverse sectional view,

Figure 4 is a perspective view of the tie holder as made in accordance with this in- 45 vention.

Referring to the drawing, the numeral 5 designates an arcuate tongue looped as at 6 to provide the spaced members 7. The terminals of the arcuate members 7 are bent 50 laterally in opposite directions to provide the horizontally extending spacing arms 8. A vertical tie retaining loop 9 is formed inte-

grally with the terminals of each of the spacing arms 8 and they are arranged at right angles thereto. The loops 9 extend 55 above and below the plane of the spacing arms 8 as is clearly shown in Figure 4.

A horizontal supporting arm 10 is formed integrally with each of the loops 9 as at 10', and the arms 10 are arranged in spaced 60 parallel relation with the arms 8 and have their inner ends terminating at a spaced distance apart and bent downwardly as at 11 to provide the attaching members.

A button or stud engaging member 12 is 65 secured to the attaching members 11 and it is located in the rear of and in the plane above the lower end of the arcuate tongue 5.

It will be apparent that the tie holder may be constructed from a single length of relatively stiff material, such as wire, metal, rubber, celluloid, pressed paper, or the like, and is first looped as at 6 to provide the tongue 5, the terminals of the tongue are bent laterally to provide spacing arms 8; 75 the arms 8 are curved downwardly and upwardly and then extended downwardly to provide the loops 9, the terminals of the loops are bent upwardly and inwardly to provide the spaced parallel supporting arms 80 10, the terminals of the supporting arms 10 are bent downwardly to provide the attaching members to which the stud engaging member 12 is secured.

A tie designated A first has its ends ex- 85 tended through the loops 9 and across the front side of the tongue 5, and the ends of the tie are then twisted about the tongue and one end is extended under the tongue and through the arms 8 and 10 respectively 90 and then extended upwardly over the arms 8 and down through the knot 13 formed by twisting ends of the tie about the tongue 5 by drawing one end of the tie through the knot and pulling tight, a knot is formed 95 about the tongue 5 and will be urged outwardly in the plane beyond the loops 9 as clearly shown in Figures 1 and 2.

What is claimed is:

A frame upon which a necktie is to be tied 100 before association with a collar consisting of a strand of material having its terminals spaced apart and offset in the same direction, a continuous button-engaging member

enclosing and mounted by said terminals, and said member due to its walls being spaced apart by said terminals providing a relatively wide means to snugly fit the button intermediate its head and the collar of the wearer to avoid undue longitudinal movement of the frame on the button.

In testimony whereof I affix my signature in presence of two witnesses.

LAWRENCE WALUCH.
